COLD STORAGE BOXES

Willard L. Morrison, Lake Forest, Ill.

Application August 16, 1954, Serial No. 450,202

1 Claim. (Cl. 312—214)

My invention relates to improvements in cold storage boxes and has for one object to provide a new and improved form of cold storage box which under some circumstances may be used for refrigeration at temperatures above freezing or under other circumstances may be used for storage of food and other heat sensitive material at temperatures below freezing.

Heretofore such boxes have been made of metal or wood with insulating material contained in the walls of the box and supported by the walls, the walls having no structural strength and relying for its support and for its maintenance in position to enclose the material contained in the box entirely upon the structural elements.

I propose on the other hand to provide a box or casing wherein the insulating means are in the main self-supporting so that the walls of the box which enclose the material being refrigerated serve simultaneously as insulating and structural elements.

Preferably, I propose to use in the construction of the box such an insulating material as balsa wood which is, though soft, substantially strong structurally and which when assembled in a box will provide a substantially, completely non-metallic casing which is self-supporting and insulating.

It will be understood, of course, that the insulating character of the balsa wood is dependent in part at least on the fact that it is a soft lightweight porous material and being soft and lightweight while of ample strength is subject to some measure of penetration by impact or distortion as a result of impact and I therefore propose to reinforce the balsa wood insulating and structural box at a few places to prevent danger of marring, scuffing and deterioration.

Balsa wood being porous, does not provide the best possible vapor barrier so under some circumstances the balsa wood box will be lined with a thin vapor barrier layer which might take the form of paint or lacquer or a thin box supported metal wall but in the main the balsa wood furnishes not only the insulating means but the structural strength for the box.

Other objects will appear from time to time throughout the specification and claims.

My invention is illustrated more or less diagrammatically in the accompanying drawings, wherein—

Figure 1 is a side elevation of the box;

Figure 2 is an end elevation;

Figure 3 is a plan view;

Figure 4 is an exploded view of the box assembly.

Like parts are indicated by like characters throughout the specification and drawings.

I have not illustrated the refrigerating machine itself. This will take the form of the usual compressor, motor to drive the compressor, expansion or storage chamber, condenser and means for cooling the condenser. This assembly will be supported with the box preferably below the cold storage chamber and the evaporator coils or the places, as the case may be, will be contained within the

2

chamber in series with the compressor and condenser supported below or if desired, at one side of the chamber.

I propose that the box will be assembled as a unit and then the refrigerating machinery will be placed in relationship with the box and connected up with the evaporator or cooler coils or plates.

1, 1 indicates the end, top plates, there being two of them at either end of the box. 2, 2 are the side box plates, there being two of them on either side joining the end top plates. 3 is the top plate divider. 4, 4 indicates the four corner posts, 5, 5 the intermediate center support posts. 6 is a plywood bottom panel supported by the posts 4 and 5. The corner posts 4 are notched diagonally as indicated to support the end louvers 7. The corner posts and the center support posts are notched diagonally to support the side louvers 8. 9 is an end cross bar, 10 a center cross bar. 11, 12 are side louver bases immediately above the skid bases 13 on which the structure rests. All these wood elements are of relatively hard or solid wood, pine or other similar type of wood habitually used for structural purposes. The end and side top plates are located at the top of the vessel or box and subject to wear and tear when food or other material is taken into or out of the box. The corner and end posts support the box

15 on the skid bases through the cross bars 9 and 10.

16 is the top lid preferably of balsa wood, there being two of them and they rest upon the two openings at the top of the box, the entire box forming one chamber, the open top being divided by the top plate divider 3. 17 is 20 a balsa side panel, 18 a balsa wood end panel, 19 a balsa wood bottom panel. These panels being notched as indicated to receive and enclose the corner and center support posts. The top plate 3 is supported and reinforced by the top divider stop 20 of balsa wood which also furnishes 25 insulation for the space or clearance between the two covers 16.

26 is a refrigeration unit with temperature controls and the like shown only in outline and not illustrated because the particular details of this refrigeration machine form 30 no part of the present invention. 27 illustrates cold plates in series with the refrigerator by way of the ducts 28 so that operation of the refrigeration machine will cause the cold plates 27 to act as evaporators and lower the temperature of the plates and so the temperature of the contents of the box. 33 indicates rubber gaskets for the lids 35. 16. These lids 16 of hard wood on their upper surface are insulated by balsa wood filling panels 32 which insulate the lids themselves and penetrate between the members 1 and 2. 34 indicates an aluminum foil lining for the 40 box. This lining may be cemented or glued to the inner walls of the balsa wood box and to the lower surfaces of the doors or lids, thus furnishing both a vapor seal for the box and a waterproof lining for the box to prevent the danger of impregnation of the insulation by 45 water as a result of condensation above the freezing temperature, of vapor migrating from the contents of the box to the cold plates. Under some circumstances such lining may be omitted or it might take the form of paint, enamel or any other suitable material coating the box 50 lining.

The wooden box, the louvers and the supporting wood mechanism will of course be painted or enameled as is usual, in the refrigeration and freezer industry.

55 35 indicates wood dowel pins joining and tying the posts and cross bars with the balsa wood side and end and other panels so that so far as is possible, there will be no metal in the structure except that above referred to and the wood screws 43 which tie the cross bars 9 and 10 and the 60 louver bases 11 and 12 together to the wooden skid base 13.

While I prefer to make the end, side and bottom panels

forming the box of a porous relatively light material having high insulation effect, such as balsa wood, it will be understood that other light, porous material of sufficient strength to form the body of the box and having sufficiently high insulating characteristics may be used.

When balsa is used, since balsa wood of commerce is usually in small pieces, these pieces will be cemented or glued together to form the panels, a suitable number and size of these pieces being used for that purpose.

I claim:

A refrigerator box comprising horizontal bottom, and vertical end and side slabs of a light porous insulating wood such as balsa, corner posts of wood stronger and more resistant than balsa, inlets into the four corners of the box whereby the posts are flush with the balsa slab, wood dowels holding the posts in place in the slabs and holding the slabs together, the posts extending downwardly below the bottom slab, the box being open at the top, hard wood reinforcing plates masking the upper edges of the side and end slabs and overlying and in direct contact with the posts, the plates being co-extensive with and at

outer and inner edges flush with the sides of the slabs, a non self-supporting metallic foil liner adhering to the inner face of bottom, end and side slabs, a refrigeration coil supported on one of the vertical slabs in contact with the foil lining, the corner posts being insulated from the interior of the box by the balsa interposed between the inner surfaces of the posts and the interior of the box.
